COTTON PICKER

George W. McKinney, Graham, N. C.

Application May 11, 1934, Serial No. 725,199

7 Claims. (Cl. 56—40)

This invention has reference to cotton picking devices and has as its primary object the provision of a device which may be readily suspended from the shoulder of the cotton picker or laborer and easily manipulated by him for picking the cotton.

The invention consists in a novel combination and arrangement of elements providing for a compact and efficient structure and of a weight 10 as not to be too burdensome for a person to carry.

The invention together with its numerous objects and advantages will be best understood from a study of the following description taken in connection with the accompanying drawings where- 15 in is illustrated a preferred embodiment of the invention.

It is to be understood at the outset that it is in no wise intended to restrict the invention to the precise details of construction, combination 20 and arrangement of elements as herein illustrated and described, other than may be necessary to meet the requirements of the prior art and scope of the appended claims.

In the drawings:

25 Figure 1 is a perspective view of the device illustrating the manner of suspending it from the shoulder of a person.

Figure 2 is a top plan view of the device.

Figure 3 is a fragmentary view partly in section and partly in elevation showing the mechanism for revolving the tool equipped shaft of the device.

Figure 4 is a vertical transverse sectional view through the device.

35 Figures 5 and 6 are sectional views taken respectively on the lines 5—5 and 6—6 respectively of Figure 2, and

Figure 7 is a perspective view of the picking tool.

40 Referring to the drawings by reference numerals it will be seen that the device comprises a relatively narrow elongated frame 5 having a broad flat end portion 6 and spaced parallel side members 7 connected at one end to the portion 6 of the frame. Brackets 8, 9 are mounted on one of the side bars 7 and journaled in the brackets are rollers 10, 11. On the other of the side bars 7 is mounted a bracket 12 in which is journaled a shaft 13 provided with a hand crank 14. On the 45 free end of the shaft between the side members 7—7 there is mounted a disk 15 provided on one face with a semi-circular hump 15 that is engageable with the roller 10, and a relatively short arcuate hump 16 arranged inwardly of the hump 15 and engageable with the roller 11.

Slidably and rotatably mounted in the frame 5 and supported by the brackets 8, 9 and a bracket 17 is a shaft 18 that is non-circular in cross section. Rollers 10, 11 have hubs provided with non-circular bores which receive the shaft 18 whereby the rollers are mounted on the shaft 18 for rotative movement therewith. On the shaft 18 between sides of the bracket 17 is a collar 20 relative to which the shaft 18 is slidable.

On the free end of the shaft 18 there is provided a suitable picking tool 21 and the same may be, as shown in Figure 5 integral with the shaft 18, or may be a separate tool as shown in Figure 7 and designated by the reference numeral 21a. In this connection suitable means will of course be provided for detachably securing the tool 21a to the shaft 18.

The tool equipped end of the shaft 18 operates through a cylinder 22 fixedly supported by brackets 23 between the ends of the side bars 7 remote from the frame end 6.

As shown in Figure 5 the cylinder 22 is provided with a discharge opening 24 through which the cotton passes into a depending spout 25 that accommodates the mouth of a bag 26 which is secured at said mouth to the side bars 7 as at 27. The bottom or closed end of the bag is supported from one side of the frame member 6 by suitable hook and eye means 28. The bag 6 is of the type shown in the drawings and is provided with a suitable closure flap 29. For reciprocating the shaft 18 there is provided a lazy tongue structure 30 anchored at one end to a cross bar 31 secured between the frame bars 7. At its other end the lazy tongue 30 is connected to a slide 31 of suitable construction mounted between the bars 7 for sliding movement relative thereto. Rotatably mounted in the slide 31 and anchored to the shaft 18 as at 32 is a collar 33 as will be clear from a study of Figure 6. For actuating the lazy tongue 30 there is provided a pitman rod 34 that is eccentrically mounted on the disk 5 as at 35.

For removing the cotton on the tool 21 when the tool is drawn inwardly of the cylinder 22 there is provided at the inner end of the cylinder 22 a block 36 the inner end face 37 of which cooperates with the tool 21 in a manner thought apparent to remove the cotton from the tool.

From the description of the invention thus far it will be seen that by operating the handle 14 the disk 5 is rotated in a clockwise direction to engage the hump 15 with the roller 10 to rotate the shaft 18 while at the same time through the medium of the pitman rod 34 and the lazy tongue 30 the shaft 18 will be projected outwardly with

respect to the cylinder 22 to engage the tool 21 with the cotton. Manifestly as the cam hump 15 moves out of engagement with the roller 10 the hump 16 will move into frictional engagement 5 with the roller 11 causing the shaft 18 to rotate in a reverse direction, while at the same time through the medium of the mechanism hereinbefore described, including the pitman rod 34, and the lazy tongue 30, shaft 18 will be drawn 10 inwardly of the cylinder 22 with the cotton on the tool 21. When the tool 21 approaches the block 36 within the cylinder and continues inwardly of the socket 38 provided in said block to accommodate the tool, the cotton on the tool 15 will engage the inner face 37 of the block and will be forcibly removed from the tool to fall through the spout 25 and into the bag 26.

For suspending the device from the shoulder of the person operating it there is provided a 20 shoulder strap 39 that is connected at one end through the medium of springs 40 with intermediate portions of the frame side members 7. The other end of the strap 39 is connected through the medium of a spring 41 with one end of a handle 25 42 that is secured to the end 6 of the frame as at 43. As shown in Figure 1 the handle 42 will be grasped by one hand of the operator of the device for steadyng the device, while the other hand of the operator is used for controlling operation of the device.

30 What I claim as new is:

1. A tool of the class described comprising an elongated frame, a shaft mounted longitudinally of the frame for reciprocatory and rotary movement therein, spaced transmission rollers mounted on the shaft to rotate therewith, means engaging the rollers to hold the same relatively fixed against longitudinal movement, a disk revolubly mounted in the frame, inner and outer humps on one face of the disk cooperating with 35 the rollers for rotating the shaft during reciprocatory movement of the latter, and a tool on one 40 end of the shaft.

2. A tool of the class described comprising an elongated frame, a shaft mounted longitudinally of the frame for reciprocatory and rotary movement therein, spaced transmission rollers mounted on the shaft to rotate therewith, means engaging the rollers to hold the same relatively fixed against longitudinal movement, a disk revolubly mounted in the frame, inner and outer humps on one face of the disk cooperating with the rollers for rotating the shaft during reciprocatory movement of the latter, and a tool on one 45 end of the shaft, a fixed open ended cylinder mounted on the frame and through which the tool-equipped end of the shaft operates, and means internally of the cylinder and engageable with the cotton or the like on the tool for removing the cotton from the tool when the latter is 50 retracted with respect to the cylinder.

3. A tool of the class described comprising an elongated frame, a shaft mounted longitudinally of the frame for reciprocatory and rotary movement therein, spaced transmission rollers mounted on the shaft to rotate therewith, means engaging the rollers to hold the same relatively fixed against longitudinal movement, a disk revolubly mounted in the frame, inner and outer humps on one face of the disk cooperating with the rollers for rotating the shaft during reciprocatory movement of the latter, a tool on one end of the shaft, a fixed open ended cylinder mounted on the frame and through which the tool-equipped 55

end of the shaft operates, and means internally of the cylinder and engageable with the cotton or the like on the tool for removing the cotton from the tool when the latter is retracted with respect to the cylinder, a shoulder strap, and means connecting the shoulder strap with the frame for suspending the device from the shoulder of the operator.

4. A tool of the class described comprising an elongated frame, a shaft mounted longitudinally of the frame for reciprocatory and rotary movement therein, spaced transmission rollers mounted on the shaft to rotate therewith, means engaging the rollers to hold the same relatively fixed against longitudinal movement, a disk revolubly mounted in the frame, inner and outer humps on one face of the disk cooperating with the rollers for rotating the shaft during reciprocatory movement of the latter, and a tool on one 10 end of the shaft, a fixed open ended cylinder mounted on the frame and through which the tool-equipped end of the shaft operates, and means internally of the cylinder and engageable with the cotton or the like on the tool for removing the cotton from the tool when the latter is 15 retracted with respect to the cylinder, said cylinder having an opening in its bottom side, and a bag suspended from the frame and having a neck engaged with the cylinder for receiving the cotton.

5. In a tool of the class described, a pair of relatively spaced fixed bracket members, rollers journaled in the bracket members, a rotary and reciprocatory shaft slidable axially through the rollers and engaged with the rollers in a manner to cause the rollers to rotate with the shaft during reciprocatory movement of the shaft, a disk mounted on an axis extending at right angles to the shaft, bearing means in which the axis for the disk is journaled, and concentric humps on 35 the disk and with which the rollers are engaged 40 for transmitting rotary movement of the disk to the shaft.

6. In a tool of the class described, a pair of relatively spaced fixed bracket members, rollers journaled in the bracket members, a rotary and reciprocatory shaft slidable axially through the rollers and engaged with the rollers in a manner to cause the rollers to rotate with the shaft during reciprocatory movement of the shaft, a disk mounted on an axis extending at right angles to the shaft, bearing means in which the axis for the disk is journaled, concentric humps on the disk and with which the rollers are engaged for transmitting rotary movement of the disk to the shaft, means for rotating the disk, and means connected 50 with the shaft for reciprocating the latter.

7. In a tool of the class described, an elongated frame, rollers mounted in the frame and extending longitudinally thereof, means for supporting the rollers for rotative movement and against longitudinal movement, a rotating and reciprocating shaft extending longitudinally of the frame and axially through the rollers and engaged with the rollers for rotation with the rollers, a driving disk for the shaft mounted in the frame on an axis at right angles to the shaft, means on the disk engageable with the rollers for rotating the latter as the disk revolves and during reciprocatory movement of the shaft, and a lazy tong structure connected with the frame and the shaft 55 for reciprocating the latter.

GEORGE W. MCKINNEY.
